UNITED STATES PATENT OFFICE

WILLIAM E. SHERBONDY, OF SHAKER HEIGHTS, OHIO

CARPET SWEEPER

Application filed December 14, 1923, Serial No. 680,753. Renewed March 29, 1930.

This invention relates to improvements in carpet sweepers of the traction driven type. Such sweepers usually comprise a rotary brush which is operatively connected to the traction wheels and is disposed adjacent the mid-portion of the sweeper. A dust collecting receptacle is usually positioned on each side of the brush wherefore the sweeper is arranged to pick up sweepings while being moved rearwardly as well as forwardly. An objection to sweepers of this type is that the dust cannot be retained within the receptacle but is scattered into the atmosphere.

One of the objects of my invention is the incorporation in a carpet sweeper of the standard type of a suction mechanism which is so disposed with relation to the brush and so operated by the usual movement of the sweeper that a continuous draft from the brush chamber is obtained, and thus the dust is effectively removed during the operation of the sweeper.

A further specific object of my invention is the provision of a mechanism for creating a suction in conjunction with the usual sweeping mechanism such that it may be readily attached to existing sweepers with very little change or modification in the construction thereof.

I accomplish these objects preferably by placing a fan housing within the sweeper casing directly above the brush, and within the housing providing a fan with gearing directly connecting it to at least one of the traction wheels, in a manner not to interfere with the relative rising of the traction wheels when the operator bears down on the sweeper handle in the usual operation of the sweeper. The ratio of the gearing is such that the fan is caused to revolve at a higher rate of speed than the traction wheels. Moreover suitable clutch mechanism is provided for enabling the fan to be actuated directly by the forward propulsion of the sweeper and by momentum during the rearward stroke thereof. In this way a suction is produced which is effective for removing dust not only when the sweep-

er is being propelled forwardly, but also while it is being moved rearwardly.

A preferred mechanism for carrying out the above objects will hereinafter be more fully set forth in the following description which pertains to the accompanying drawings. The essential features will be summarized in the claims.

In the drawings, Fig. 1 is a plan view of a carpet sweeper embodying my invention; Fig. 2 is an end elevation of the sweeper shown in Fig. 1; Fig. 3 is a transverse section taken on the line 3—3 on Fig. 1; Fig. 4 is a central longitudinal section as indicated by the line 4—4 on Fig. 1; Fig. 5 is a perspective of the bracket carrying the upper bearing for the fan shaft; Fig. 6 is a cross section of the clutch as indicated by the lines 6—6 on Fig. 4; Fig. 7 is an end elevation of a modified form of the sweeper showing an alternate means for drivingly connecting the fan and traction wheels. Fig. 8 is a section of one end of this form of the sweeper taken along the lines 8—8 of Fig. 7; Fig. 9 is a sectional plan showing one form of the attaching bracket for the pusher bail.

I have illustrated my invention in connection with a carpet sweeper embodying a casing having end walls 10 and 11 which cooperate with a frame 12. The end walls illustrated have slotted openings 13 and 14 for receiving shafts 15 and 16 respectively. A spring retainer 17 is shown as secured intermediately at 18 to an end wall, and as having the ends thereof engaging the shafts to provide a "floating bearing" therefor. The shafts 15 and 16 each have traction wheels 19 and 20 carried thereby, outside the walls 10 and 11.

A brush 21 mounted on a shaft 22 is enclosed within the casing intermediate the shafts 15 and 16. The brush shaft is shown as journaled in downwardly opening slots 23 and 24 at opposite ends of the casing, and as having at its ends rollers 25 frictionally engaged by the wheels 19 and 20 respectively.

When the sweeper is in use, the downward pressure on the handle causes the casing and

the brush (which in idle position clears the floor, as shown in Fig. 2) to move downwardly so that the brush engages the floor, the spring 17 yielding and the slots 13 and 14 allowing such movement relative to the wheel axles.

The heavy sweepings picked up by the brush may be collected in receptacles 26 each of which is disposed beneath the corresponding shaft 15 or 16 and pivotally mounted at 27. The pans may be emptied in the usual manner, as for instance by actuation of a lever 28, the operating ends of which project through the casing 12 as indicated in 15 Fig. 3. Springs 29 are shown as normally keeping the pans in closed position.

My invention is particularly concerned with the provision of means for collecting dust and other light sweepings which do not 20 settle within the collectors 26 during the normal operation of the sweeper. To this end, I provide a fan 30 which is rotatably supported within a fan housing 31 and is disposed directly above the top of the brush 25 so as to draw the dust into the fan chamber, not only from the brush, but also from the compartments on either side of the brush. The housing is arranged to be attached to the top of the frame 12 and to extend into 30 the sweeping compartment sufficiently to bring the inlet aperture 32 directly above the brush. The housing is shaped so that the discharge passageway 33 extends to the rear side of the sweeper and is arranged for 35 attachment to a bag 80 (Fig. 1), the other end of which may be supported by the handle extending from the bail 75.

The fan is shown as rigidly mounted on a vertical shaft 34, the upper end of which 40 is journaled at 35 in a bracket 36 and the lower end of which is journaled in a thrust bearing 37, which is supported by a portion of the casing 38. The shaft 34 may be rotated by a bevel pinion 40 thereon which 45 meshes with a gear 39, as shown in Fig. 4. This gear is mounted on a shaft 41, one end of which is journaled in the bearing 42 and the other end of which may be attached to a driven member 43 of a clutch. The co- 50 operating driving member 44 of the clutch is carried on shaft 45, the axis of which is in alignment with the shaft 41. Suitable brackets or bearing blocks 46 and 47, rising from an extension of the fan housing casting, support the shaft 45, thus easily aligned 55 bearings for the two shafts are provided.

I have found it convenient to cover the drumlike housing 31 and the gearing with a sheet metal guard or dust cap 57. This 60 guard may extend downwardly as at 58 to cover the sprocket wheels and chain.

To rotate the shaft 45 I provide a driving connection between it and one of the traction wheels of such character as will allow 65 relative movement between such shaft and

wheel. As shown, a gear 48 on the shaft 45 which meshes with a gear 49 on a lay shaft 50, also carried by the bracket 46 (as shown particularly in Fig. 3), and this lay shaft carries a sprocket wheel 51 which 70 is rotated by a chain 52 from a sprocket wheel 53. This last mentioned sprocket wheel is shown as rigid on the shaft 15 and as disposed intermediate the wall 10 and the traction wheel 19. 75

The clutch member indicated by the co-operating parts 43 and 44 embodies a usual clutch construction for transmitting rotation only when the driving shaft is actuated in one direction. As shown in Fig. 6, the 80 clutch members may be connected by rollers 55 occupying tangentially positioned notches 56 in the clutch member 43.

The clutch is so arranged that when ever the sweeper is moved forwardly the shaft 85 41 is rotated simultaneously with the shaft 45. This in turn effects rotation of the fan through the gearing 39 and 40. On the other hand when the sweeper is moved rearwardly, then the clutch is disengaged while 90 the direction of rotation of the shaft 45 is reversed. During such rearward movement of the sweeper, however, the momentum of the fan and the associated parts is such as to cause continuous operation of the fan for 95 considerable time. Since the ratio of the gearing between the traction wheel and the fan causes considerable multiplication of speed, and the fan acts as a fly wheel, the suction created by the fan is adequate to 100 remove the dust and convey it to the bag during the rearward as well as the forward stroke of the sweeper.

An important characteristic of the present invention is the adaptability of the fan 105 to sweepers wherein the traction wheels are supported on a floating bearing, such bearings being illustrated by the spring 17 and the slots 13 and 14 respectively. Thus, when pressure is placed on the sweeper handle 110 sufficiently to force the shaft 15 upwardly with relation to the end wall of the sweeper casing, so as to bring the brush into close contact with the surface to be cleaned, then such relatively upward movement of the 115 shaft 15 will merely slacken the chain 52 without interfering with the positive drive between the wheel 53 and the pinion 51.

In Figs. 7 to 9 I have shown a modified form in which the clutch shaft 45 is driven 120 from the brush shaft by a sprocket chain. In this construction the driving means is somewhat simpler while on the other hand it is more difficult to remove the brush for cleaning. It will be noted that in both constructions the traction wheels are allowed to move relative to the brush and casing without interfering with the driving of the fan. 125

The usual construction of the brush shaft 130

is that shown in Fig. 8 wherein the roller 25 may comprise a ring surrounding the reduced portion 60 of the brush shaft and fastened securely thereto. I have utilized the inner surface of this ring for securing a sprocket 61 to the shaft preferably by screws as shown. In place of the gears 48 and 49 I mount a single sprocket 62 on the free end of the clutch shaft 45 thus driving the fan mechanism from the traction wheels, friction roller 25 and sprocket chain 63.

In order to pivotally mount the pusher bail conveniently near the center of gravity of the sweeper I have provided an attaching bracket therefor, formed of a single stamping and indicated at 70 in Figs. 7 and 9. This bracket is in the nature of a stirrup having legs 72 and a connecting portion 73. A downward extension 74 from the connecting portion serves to receive a bearing pin 77 on the ends of the bail 75 while the outwardly extending flange 76 may serve as a detent for the bail to hold it upright in idle position. The portion 58a of the dust cap or guard covering the sprocket chain may extend into this stirrup as shown to lend a finished appearance to the sweeper.

From the foregoing description taken in connection with the drawings, it will be apparent that I have provided means for effecting the removal and collection of dust from a carpet simultaneously with the actuation of the sweeper, and that such means is readily adapted for attachment to existing carpet sweepers. Moreover the arrangement of the operating parts is such that the fan is rotating constantly while the sweeper is actuated intermittently. An advantage of a machine made in accordance with my invention is the simplicity and economy of construction, the machine being much cheaper than standard vacuum cleaners, while having the valuable dust-collecting feature not present in standard carpet sweepers.

Having thus described my invention, I claim:

1. In combination, a carpet sweeper casing, a brush carried thereby, said casing having an opening above the brush, a housing carried by the casing and projecting through the opening into the casing, said housing having a bottom inlet opening in close proximity to the top of the brush, a vertically extending shaft enclosed within the housing, a fan mounted on said shaft, traction wheels carried by the casing, and means drivingly connecting at least one of the traction wheels with said shaft above the fan.

2. In combination, a carpet sweeper casing, a brush mounted within the casing, traction wheels therefor, said wheels hav-

ing floating bearings connecting them to the casing, a fan mounted on a vertical shaft above said brush and means operatively connecting the fan shaft with at least one of the traction wheels, said means including a sprocket wheel and chain connection adapted to allow movement of the traction wheels with relation to the casing without disconnecting the driving connection to the fan.

3. In combination, a carpet sweeper casing, a brush mounted within the casing, traction wheels therefor, said wheels having floating bearings connecting them to the casing, spring means tending to force the bearings downwardly, a fan mounted on a vertical shaft above said brush, a ratchet clutch geared with the fan shaft and a connection including a sprocket wheel and chain between the clutch and at least one of the traction wheels, whereby movement of the traction wheels with relation to the casing may occur without affecting the driving connection to the fan.

4. In combination, a carpet sweeper casing having an opening adjacent the top thereof, a brush carried by the casing, a housing attached to the casing and projecting through the opening into the interior of the casing and terminating short of the brush, a vertically extending shaft rotatably mounted within the housing, a fan rigid with the shaft, a horizontal shaft extending outside the housing and operatively connected to the vertical shaft, driving means for the horizontal shaft, said means including a one-way ratchet clutch for positively actuating the horizontal shaft when the sweeper is moved in one direction.

5. In combination, a carpet sweeper casing having an opening therein, a brush carried by the casing, a housing projecting through the opening and having a portion thereof outside the casing, a vertically extending shaft supported by the housing, a fan rigid on said shaft within the housing, said fan also projecting partially into the casing, a bearing block outside the housing, a horizontally extending shaft, bevel gearing operatively connecting the horizontal shaft with the vertical shaft, a clutch having one member mounted on the horizontal shaft and having the cooperating member supported on the bearing block, and means for driving said cooperating member.

6. In combination, a carpet sweeper casing, a brush therein on a horizontal axis, dumpable pans on opposite sides of the brush, pairs of traction wheels at opposite ends of the casing respectively, the two wheels of a pair being on opposite sides of the brush and serving to drive the same, a housing mounted on top of the casing and communicating through such top with the space within the casing above the brush, a

dust receptacle in communication with said housing, a horizontal fan within said housing, means whereby said fan is driven by said traction wheels, said means including a horizontal shaft above the carpet sweeper casing and the fan housing, bevel gearing connecting said shaft with the fan and a clutch one member of which is connected to said shaft, and a driving connection from the traction wheels to the other member of said clutch whereby in the operation of the sweeper the momentum of the fan imparts a continued movement thereto though the direction of movement of the sweeper is reversed.

7. In combination, a hollow carpet sweeper casing, a brush carried thereby, traction wheels carried by the casing and drivingly connected with the brush, means for adjusting the vertical relation of the traction wheels to the casing to allow the brush to sink into the carpet being swept, a housing rigidly carried by the casing above the brush and communicating with the space within the casing, a dust receptacle in communication with said housing, a rotary suction fan within said housing, and transmission mechanism connecting said fan to a traction wheel and maintaining such connection notwithstanding the changing relation of such traction wheel to the casing and housing.

8. In combination, a carpet sweeper casing, a brush therein, traction wheels on vertically yieldable bearings carried by the casing, a horizontal fan, a fan housing communicating in an axial direction with the space within the casing above the brush, a dust bag into which the fan housing opens at the rear, an over-running clutch, one member of which is connected to the fan and a driving connection between the traction wheels and the other member of the clutch operable independently of vertical movement of said wheels with relation to the casing.

9. A carpet sweeper having a casing, a pair of horizontal shafts vertically shiftable therein and projecting beyond the casing, four traction wheels mounted on the ends of said shafts, a central horizontal brush within the casing having a pair of rollers in frictional engagement with said wheels, and dumpable pans on opposite sides of the brush, combined with a horizontal fan mounted on a vertical axis over said brush, a fan housing mounted on the top of the casing and communicating in an axial direction with the space about the brush and above the pans, a dust bag into which the fan casing discharges laterally a horizontal shaft above the fan housing and said casing geared with said fan, an over-running clutch one member of which is connected to said horizontal shaft, and means drivingly

connecting the other member of said clutch to said traction wheels for driving the fan continuously in one direction only consequent upon the repeated forward movements of the casing and independent of the intervening backward movements thereof.

In testimony whereof, I hereunto affix my signature.

WILLIAM E. SHERBONDY.
